UNITED STATES PATENT OFFICE.

FELIX MARY MUSY AND MELVILLE E. SULLIVAN, OF RICHMOND, VIRGINIA.

RAILWAY-TRAIN AUTOMATIC-CONTROL APPARATUS AND SYSTEM.

1,324,205.

Specification of Letters Patent.

Patented Dec. 9, 1919.

Application filed May 29, 1917. Serial No. 171,669.

To all whom it may concern:

Be it known that we, FELIX M. MUSY, a citizen of the French Republic, and MELVILLE E. SULLIVAN, a citizen of the United States, residing at Richmond, in the county of Henrico and State of Virginia, have invented new and useful Improvements in Railway-Train Automatic-Control Apparatus and Systems, of which the following is

10 a specification.

Our invention relates to the control of railway trains, and particularly to that type of apparatus and systems for this general purpose in which means are provided for 15 closing the throttle and applying the brakes on the train whenever a danger condition exists, thereby stopping the train and affording protection to the company and the general public by preventing accidents.

20 The objects of the invention are to provide a system and apparatus which will operate under a danger condition to prevent head-on and rear-end collisions between trains, accidents due to displaced switches, 25 or to broken rails. The system is designed to provide for every danger condition, and to positively stop a train which attempts to enter a block where such a condition exists.

It not only permits a train to proceed as it 30 enters a block free from danger, but as long as the train is in that block it is protected by the circuit condition from the subsequent occurrence of danger conditions in the block. The system is therefore complete in itself 35 and no block signals along the road are necessary.

In carrying our invention into effect we provide a fluid pressure operated and electrically controlled apparatus on the engine 40 by means of which the throttle lever may be operated to cut off the supply of steam from the engine, and the engineer's valve moved to either the service stop position or the emergency stop position when the circuits 45 of the electrical control indicate a danger condition.

The operating and control apparatus includes a cylinder and an operating piston connected to move the engineer's valve handle into the brake application position, this 50 valve handle being afterward returned manually to the off or the lap position. The apparatus does not interfere with the manual operation of the engineer's valve in the usual way. The movement of the piston further controls the application of fluid

pressure to operate the throttle lever to close the throttle or otherwise shut off steam from the engine.

The control of the operating piston is effected by means of an electromotive device comprising as shown, solenoids mounted on the operating piston and energized by current from a storage battery or other source of current carried by the engine under certain circuit conditions, to be herein-after fully explained.

The system includes the provision, at intervals along the track, of circuit changers arranged to open and close the circuit on which the operation of the electromotive device depends, and which are themselves electrically operated by the trains. These operations are effected through conductors extending along the road by means of contacts engaged by the trains in passing.

The track is laid off in blocks of desired length, say one or one and one-half miles, and a circuit changer is located at about the entrance of each block, so considered. The control contact sets or ramps are located preferably, one on the right side of the track near the end of each block to coöperate with the circuit changer at the end of the block ahead, and one on the left side of the track to coöperate with the circuit changer next in the rear.

The invention consists in the novel construction and arrangement of apparatus and parts thereof, and circuit connections, above indicated and hereinafter described and claimed, and illustrated in the accompanying drawings in which—

Figure 1 is a rear view of an engine or locomotive equipped with our invention, a roadway ramp or set of contacts being also shown, a portion of the cab wiring being omitted to avoid unnecessary complication of this figure:

Fig. 2 is a diagram showing the train carried mechanism, indicated in Fig. 1, with complete circuit connection and operative parts, the fluid pressure cylinder for operating the engineer's valve being shown partly in section;

Fig. 3 is a plan view of the engineer's valve and operating means shown in Fig. 2;

Fig. 4 is a still further enlarged detail showing the fluid pressure cylinder with operative parts in longitudinal section;

Fig. 4^a is an enlarged detail of a portion of the mechanism shown in Fig. 4, the mov-

able element being shown in another position;

Fig. 4^b is a transverse section taken on the line *b*—*b*, Fig. 4;

5 Fig. 5 is a side elevation of the ramp or set of contacts employed in connection with each block of the system;

10 Fig. 6 is a vertical section of the circuit changer employed in connection with each block;

Fig. 6^a is a detail of the contact elements shown in Fig. 6;

15 Fig. 7 is a perspective view of the contact arm or bracket secured to the locomotive, for carrying the train carried contacts adapted to engage the contact of the ramp;

20 Fig. 7^a is a similar view of the movable contacts mounted upon a block to be secured to the contact arm or bracket shown in Fig. 7;

Fig. 8 is a cross section of a double track portion of the roadway, showing a preferred mounting of the conductors employed in the roadway portion of the system;

25 Fig. 9 is a diagrammatic view of a portion of the railway track equipped in accordance with our invention, the roadway system here shown being employed for a single track road upon which trains may move in either direction, and which is also employed for each track of a double track road;

30 Fig. 10 is a diagram showing the wiring employed in connection with a siding or turnout, and in which trains may move in either direction on the main line, or in either direction onto or off of the turnout; and

35 Fig. 11 is a diagram showing various arrangements of turnouts and sidings for a yard and with power control, a portion of the circuit wiring being omitted to avoid unnecessary complication of the drawing.

40 Referring to the drawings, it will be seen that we have illustrated the train carried portion of our system and apparatus as mounted upon a railway locomotive. 10 indicates the cab of a steam locomotive, 11 the engineer's brake valve for controlling the 45 application and release of the air brakes of the train, and 12 the throttle valve for admitting steam to or cutting it off from the engine. The throttle lever is indicated at 13. These are usual elements upon the locomotive and need not be further described. 50 14 is the operating handle of the engineer's valve.

Fluid pressure means are provided for operating the engineer's valve automatically 55 upon the occurrence of a danger condition, these means comprising a fluid pressure cylinder 15 suitably mounted adjacent the engineer's valve and connected by pipe 16 with any suitable source of fluid pressure, such 60 as the source of air pressure employed for

the air brake system. Within cylinder 15 is mounted a piston 17 having a hollow piston rod 18, the bore of said piston rod being extended through the piston.

Mounted upon the under face of the piston is an electro-motive device for controlling the movements of the piston, this device comprising, in the construction shown, a solenoid 19 adjacent said piston, and a second solenoid 20 mounted below solenoid 19. 70

Fluid pressure above the piston is admitted to the hollow piston rod by means of ports 21, controlled by valve 22 in the form of a tube or sleeve which extends downwardly through the solenoids and upon 80 which the cores 23 and 24 are mounted. From the upper end of tube 22 an extension 25 connects with an exhaust valve 26 near the upper end of hollow piston rod 18, where it controls exhaust ports 27. 85

The core 23 of solenoid 19, and the core 24 of solenoid 20 are so mounted that, when the other parts of the mechanism are properly adjusted, their pull upon the common control tube 22 will be equal when both solenoids are energized, but when solenoid 19 alone is energized core 23 will be drawn upwardly to close ports 21 through which pressure is admitted below the piston, and to open exhaust 27 to exhaust pressure, from 95 below the piston rod.

Fig. 10 is a diagram showing the wiring employed in connection with a siding or turnout, and in which trains may move in either direction on the main line, or in either direction onto or off of the turnout; and

Fig. 11 is a diagram showing various arrangements of turnouts and sidings for a yard and with power control, a portion of the circuit wiring being omitted to avoid unnecessary complication of the drawing.

Referring to the drawings, it will be seen that we have illustrated the train carried portion of our system and apparatus as mounted upon a railway locomotive. 10 indicates the cab of a steam locomotive, 11 the engineer's brake valve for controlling the application and release of the air brakes of the train, and 12 the throttle valve for admitting steam to or cutting it off from the engine. The throttle lever is indicated at 13. These are usual elements upon the locomotive and need not be further described. 14 is the operating handle of the engineer's valve.

Fluid pressure means are provided for operating the engineer's valve automatically 55 upon the occurrence of a danger condition, these means comprising a fluid pressure cylinder 15 suitably mounted adjacent the engineer's valve and connected by pipe 16 with any suitable source of fluid pressure, such 60 as the source of air pressure employed for

the air brake system. Within cylinder 15 is mounted a piston 17 having a hollow piston rod 18, the bore of said piston rod being extended through the piston.

Mounted upon the under face of the piston is an electro-motive device for controlling the movements of the piston, this device comprising, in the construction shown, a solenoid 19 adjacent said piston, and a second solenoid 20 mounted below solenoid 19. 70

Fluid pressure above the piston is admitted to the hollow piston rod by means of ports 21, controlled by valve 22 in the form of a tube or sleeve which extends downwardly through the solenoids and upon 80 which the cores 23 and 24 are mounted. From the upper end of tube 22 an extension 25 connects with an exhaust valve 26 near the upper end of hollow piston rod 18, where it controls exhaust ports 27. 85

The core 23 of solenoid 19, and the core 24 of solenoid 20 are so mounted that, when the other parts of the mechanism are properly adjusted, their pull upon the common control tube 22 will be equal when both solenoids are energized, but when solenoid 19 alone is energized core 23 will be drawn upwardly to close ports 21 through which pressure is admitted below the piston, and to open exhaust 27 to exhaust pressure, from 95 below the piston rod.

Fig. 10 is a diagram showing the wiring employed in connection with a siding or turnout, and in which trains may move in either direction on the main line, or in either direction onto or off of the turnout; and

Fig. 11 is a diagram showing various arrangements of turnouts and sidings for a yard and with power control, a portion of the circuit wiring being omitted to avoid unnecessary complication of the drawing.

low piston 17 slowly to cause a slow movement of the piston.

In order to automatically operate the throttle lever, an operating cylinder 34 is provided mounted in any suitable manner upon throttle lever 13 as by means of a strap 35 pivotally connected at 36 with a collar 37 within which latter the cylinder 34 is mounted. The piston of this cylinder is connected in any suitable manner to a fixed support such as to the boiler or cab construction at 38, so that when the piston is operated by fluid pressure admitted through flexible pipe 39 the throttle lever 13 will be moved to close the throttle.

Fluid pressure is admitted to flexible pipe 39 by means of a valve structure 40, mounted upon cylinder 15. This valve structure comprises a chamber 41 to which air pressure is admitted from pipe 16, and from chamber 41 the pressure is controlled by means of a valve sleeve 42 having upon its lower closed end a rod 43 engaged by piston 17 in its raised position. Valve sleeve 42 has admission ports 44 and an outlet port 45. 46 is a port in the casing communicating with pipe 39 and 47 is the exhaust port. Spring 48 is mounted to maintain the tubular valve member 42 depressed when released by piston 17, and 49 indicates a pressure equalizing channel for the movable valve member. When piston 17 is in its normal or raised position, pressure is cut off between pressure chamber 41 and supply port 46, as indicated in Fig. 4, and pipe 39 is connected to exhaust 47. When piston 17 is lowered valve member 42 is moved downwardly by spring 48 so as to close exhaust port 47 and open supply port 44 so that pressure is admitted to operate the throttle closing lever.

The movement of piston 17 is electrically governed by solenoids 19 and 20 through various circuits in the cab coöperating with circuits along the road, these two sets of circuits coöperating with each other by means of contacts along the road and contacts carried by the locomotive to engage said road contacts. These road contacts are commonly known as the ramp, and in our system are arranged in sets as will be described hereinafter.

The source of current is preferably carried by the locomotive and may be a storage battery 50 which may be kept charged by a generator 51 driven in any suitable manner as by a small turbine 52 supplied by steam from the boiler.

The ramps or sets of contacts along the road are arranged so that a train about to enter a block may close the block beyond said block in advance to a train running in the opposite direction, and after or when entering the block may clear that just left to the rear. This we preferably accomplish

by employing two ramps for each block, one on the righthand side near the end of the block to operate the circuit changer of the block next in advance, and one on the left to operate the circuit changer at the entrance of the block just vacated. For a train going in the other direction the same arrangement works the same.

Each ramp preferably comprises a vertical rather long operating contact 53 and a horizontal contact 54 arranged (considering the ramp on the righthand side of the track in either direction of train motion) in advance of contact 53. Contact 53 is mounted on suitable upright framing 55, and contact 54 is mounted on suitable horizontal framing 56, preferably on the under side thereof. The vertical contact 53 is of sufficient width to be engaged by brushes 58 and 59, the contact 54 which is horizontally arranged being engaged by brushes 60. These brushes 58, 59 and 60 comprise the train carried contacts which coöperate with the block contacts of the ramp and are mounted preferably at the side of the locomotive the proper distance above the roadway. One form of mounting is shown in Figs. 7 and 7^a, in which 58' is a suitable bracket secured in any desired manner at the side of the engine as shown in Fig. 1, the contacts 60 being mounted upon the upper surface of an insulation block 58''. Brushes 58 and 59 are mounted upon the outer face of this insulation block 58''. One set of these brushes 58, 59 and 60 is mounted upon the righthand side of the locomotive, and a second set is mounted upon the lefthand side of the locomotive, as shown in Fig. 1, for the purpose hereinafter to be explained.

Solenoid 19 is arranged to be put in closed circuit with battery 50 by means of wires 61, 62, brushes 58 and 59 and wire 63 whenever said brushes engage a vertical operating contact 53. Solenoid 20 is connected by means of wire 64, wheel 65 of the locomotive, track rail 66, conductor 67, operating contact 53, brush 59, wire 62, battery 50 and conductor 61. In this latter circuit it will be seen are included the track rail and conductor 67 in connection with which the safety and danger conditions of the system are associated. Therefore, it will be seen that whenever a safety condition exists the circuit of solenoid 20 will be complete, and as solenoid 19 always has its circuit completed by the ramp contacts, the pull of the two solenoid cores will neutralize each other and no operation of the train control mechanism will occur. On the other hand, should a danger condition exist solenoid 20 will receive no current when contact 53 of the ramp is engaged by the train carried contacts, the solenoid cores will become unbalanced resulting in the upward movement of core 23 and the consequent

closure of equalizing ports 21 and opening of exhaust ports 26, so that the pressure upon both sides of piston 17 is no longer equal and pressure is admitted only to the upper side of said piston, which therefore moves downward and operates the brakes and the closing of the throttle. When the piston reaches its lowermost position contact 68 engages contact 69 at the lower end of the cylinder and solenoid 20 receives current through conductor 70. The position of the cores is thereby restored within the solenoids, equalizing ports 21 are again opened and exhaust ports 26 again closed, when the piston will be returned to its raised position by the action of spring 31, leaving the engineer's valve in the brake application position in which it remains until manually restored. Cylinder 34 which had at the same time received operating pressure through pipe 39, as above explained, is also exhausted to atmosphere leaving the throttle lever in the closed position until manually moved by the engineer.

In Fig. 2 the connections of solenoids 19 and 20 are merely indicated diagrammatically. These connections may be made in practice in any suitable manner, one way being shown in Figs. 4 and 4^b, where it will be seen that springs 71, 72, and 73 are mounted at the lower end of the cylinder 15 for engagement with contacts upon the solenoid structure, one of these contacts being connected to one side of one solenoid, another contact being connected to one terminal of the other solenoid, and the third contact being the common return for both solenoids.

In order to test the apparatus on the engine from time to time to see whether the same is in working order, a switch 62' is provided the closure of which energizes solenoid 19.

Referring now to the track circuit arrangements, and first to Fig. 9, the track is divided into a number of blocks, three such blocks being indicated at X, Y and Z, the wiring being such as to provide for the operation of the system by trains going in either direction along the track. The operating circuit 67 connected to the vertical or operating contact 53 of each ramp, and shown in heavy lines in Fig. 9, is one of the circuits in which the danger condition is to act in order to control the train movements. The danger condition may be a broken rail, an open switch, or the presence of another train in undesirable proximity to the block under consideration. The operating circuit therefore, of which wire 67 is a part, is made to include one of the track rails of the block and also a circuit changer capable of being affected by the proximity of another train. Such a circuit changer is shown at 74, and

is illustrated in detail in Figs. 6 and 6^a. Referring to these figures it will be seen that this circuit changer is a step-by-step circuit maker and breaker actuated by an electromagnet 75. The core 76 of this magnet is arranged to actuate lever 77 by means of rod 78 so as to move contact wheel 79 one step in the direction of the arrow by means of pawl 80 carried on arm 81 and lever 77. The contact wheel 79 is held in its advanced position by means of pawl 82. Contact wheel 79 is made of insulating material and carries a set of contacts 83 arranged to engage contact springs 84 and 85 upon opposite sides of the contact wheel. An additional set of contact springs is also provided for use in connection with other circuits if desired.

One of these contact springs is connected to one or the other of the track rails, and the other spring is connected to operating circuit 67 and through said circuit with operating contact 53 of the ramp.

The solenoid 75 of each circuit changer is connected with contact 54 of its ramp by wire 89 extending along the way, and on the other side of said solenoid is connected to the other track rail. For instance, if contact spring 85 be considered as connected to rail 66, and contact spring 84 connected to circuit wire 67, then one side of the solenoid will be connected to rail 66' while the other side of the solenoid is connected to ramp contact 54, as above indicated.

It will be observed that the contacts of each ramp are connected by the respective circuit wires with the circuit changer with which they are to coöperate at the opposite or far end of the block, and that the return for each circuit is through one of the track rails. Each ramp is located preferably near the end of a block, perhaps two hundred yards or more from the end, so that it will be engaged by the train carried contacts at such distance before entering the block ahead as to permit the train to stop or nearly stop at the end of the block and before entering the block ahead should the danger condition exist in the last-mentioned block.

It will also be observed that each block is provided with a ramp for each direction of motion along the track, the ramp upon the righthand side of the track, considering motion in either direction, coöperating with the train carried circuits and source of current to operate the circuit changer at the end of the block ahead to the danger condition, and the ramp at the lefthand side of the track being connected to restore to safety condition or clear the circuit changer of the second block in the rear.

The operation of the system may be described as follows: Supposing blocks X, Y and Z to be free from danger conditions, and assuming that all of the circuit changers

- are in the open circuit position, a train going in the direction of the whole arrow and about to enter block X will first engage contact 54 of ramp A and current will flow from the train battery through wire 89 of the circuit changer operating circuit to the solenoid of circuit changer 74^b, and return to battery through wire 81, rail 66', and the wheels of the locomotive. This will operate circuit changer 74^b to the closed circuit position. The train-carried contacts next engaged energizing contact 53 of ramp A, when in accordance with the operation above described in connection with the train controlled mechanism upon the locomotive, both solenoids 19 and 20 are energized, the solenoid 19 through the ramp contact 53, and the solenoid 20 through this contact, wire 67, contacts 84 and 85 of circuit changer 74^b, and return to battery by rail 66 and the wheels of the locomotive. The safety condition will therefore be registered and the train will proceed into block X without hindrance.
- 25 As the train approaches the end of block X it will engage the contacts 54 and 53 of ramp B and operate the circuit changer 74^c of block Y in a manner similar to the operation of circuit changer 74^b just explained in connection with block X. Finding block Y likewise clear, the train will proceed and upon entering block Y will engage contacts 53 and 54 of ramp B' upon the lefthand side of the track. Since circuit changer 74^c is still in the closed circuit position, no actuation of the train control mechanism will take place upon contact with contact 53 of ramp B'. Upon engagement with contact 54 the solenoid of circuit changer 74^c receives current through wire 89 and track rail 66' to actuate that circuit changer one step back to open circuit or clear position. This clears the block preceding block X therefore, but block X remains with its circuit changer 74^b in the closed circuit position. If therefore while the first train is proceeding along block Y, a following train should approach block X, it would first engage contact 54 of ramp A and thereby operate circuit changer 74^b to the open circuit position. When the following train then engages operating contact 53 of ramp A the solenoid 20 of the train control mechanism will receive no current, the circuit of this solenoid being open at the contacts of circuit changer 74^b. The above described operation of the train control mechanism therefore takes place, and the train is brought to a stop automatically.

The same operation would take place if either of the track rails be broken, or a switch displaced, as follows. A train engaging contact 54 of ramp A, would be unable to supply current to operate circuit

changer 74^b at the far end of block X if there were a defective rail or open switch at the lefthand side of the track or in connection with track rail 66'. Therefore when contact 53 of ramp A is thereafter engaged no current is obtained through solenoid 20 of the train control mechanism, and the train is stopped. Supposing the lefthand rail 66' be intact, the circuit changer 74^b would be operated, but when contact 53 is engaged no current will be received through the operating circuit if the danger condition exists in connection with rail 66, and the train control mechanism will operate to stop the train. The circuit changer for each block being at the far end of the block, it will be readily understood from the foregoing that the train is fully protected against all danger conditions of the track in the block which it is about to enter.

Supposing now a train going in the whole arrow direction to occupy block Y, having actuated circuit changer 74^b and 74^c to the closed circuit position, a train attempting to enter block Z going in the opposite or split arrow direction by engagement with contacts of ramp D, will first operate circuit changer 74^c to the open circuit position and then be brought to a stop by engagement with the second contact of said ramp. This train will therefore be unable to enter block Z, and, having operated circuit changer 74^c to the closed circuit position, the train in block Y when it reaches the end of said block will in the same way be stopped by engagement with the contacts of ramp C. It will therefore be seen that two trains going in the opposite direction cannot approach each other nearer than the distance of one block.

The same operation will take place if a train going in a given direction should enter a block, stop and then back into the preceding block again. It would always be protected by the block in advance and the block in the rear, by reason of the engagement with the ramps on both sides of the track.

In order to indicate to the engineer visually the condition of the block which he is about to enter and to show that the system is working properly, I provide signal lights L, L' in the cab which are connected in the circuit of solenoid 20, so that every time that a safety condition exists these lights will show that fact to both the engineer and the fireman. If a danger condition exists the lights will fail to show, and the stop action will take place.

In applying our system to a double track road we preferably wire each track as indicated in Fig. 9, thereby avoiding the possibility of danger by a train running in the wrong direction upon either track. In this connection it may also be stated that in or-

der to avoid the possibility of accident due to the wreck of a train upon one track falling upon and obstructing the other track, we may mount the four conductors extending along the line upon low posts between the track. If a track should fall over from one track upon the other therefore one of these operating circuit conductors will be broken, thereby disabling the operating circuit and stopping trains going in either direction upon the other track. Such a mounting of these conductors is shown in Fig. 8.

In Fig. 10 we have shown the application of our invention to a turnout to enable one train to pass another on a single track road. Here the principle is the same as that shown in Fig. 9, with the addition of the switches X' and Y' which have contacts x' and y' connected in the operating circuit of the circuit changer 74'. As shown in this figure, the switch X' is shown in the closed or safety position for a train proceeding along the main line, and the circuit of the operating contact adjacent the switch is therefore complete. The switch at Y' is shown in the open position ready for a train to enter the turnout in moving from right to left, as viewed on the drawing. The operating circuit has heretofore been open at contact y'. After a train moves upon the turnout the circuit changer 74' is restored to normal or safety position by the two-contact ramp shown at either end of the turnout, so that, the switch having been moved to safety position, the through line again stands at clear or safety.

Fig. 11 illustrates the invention as applied to yard turnouts and sidings, which do not require specific description as the principles are identical as those already described. The circuit changers 74^a and 74^b are shown in connection with the switch tower, and the operating circuits of the operating ramp contacts only are shown, the omitted circuits of the other ramp contacts being the same as those already described in connection with Figs. 9 and 10. When the operator in the tower moves the various track switches of the turnouts and sidings, the electrical switches shown are also operated to in a corresponding manner open the operating switches shown connected with the operating ramp contacts. The corresponding track switches and electrical switches are indicated by the corresponding references a, a'.

In accordance with the patent statutes we have described and illustrated our invention in the best form now known to us, but it is obvious that many changes in details of construction and arrangement of parts may be made without departing from the spirit of the invention, and all such changes we aim to cover within the scope of the ap-

pended claims. For instance, the relative resistances of the various circuits may be adjusted for proper adaptation to their best operation, as will be readily understood. For instance, the circuit of solenoid 19 will be a short local circuit upon the engine and through the contacts of the ramp, and hence will require less current than the circuit of the solenoid 20 which will include a considerable length of line conductor as well as the resistance of the rails. It will therefore be necessary to wind the solenoid 19 to very high resistance as compared with the resistance of solenoid 20, or otherwise compensate for the relative differences of resistance in the two circuits, which will be often in shunt relation. Further, it will sometimes be advisable to use two or more circuit changers for each block, instead of one as shown, and to arrange these at suitable locations within the block, as may be desired. Other changes will readily suggest themselves to those skilled in the art.

Having described our invention, what we claim as new and desire to secure by Letters Patent of the United States, is:

1. In a train control block system, a brake applying control means comprising a fluid pressure cylinder, a piston within said cylinder, a valve means carried by said piston for controlling admission of fluid pressure to and exhaust from one side of said piston, and an electromotive device mounted upon and movable bodily with said piston within said cylinder for controlling said valve means.

2. In a train control block system, a brake applying control means comprising a fluid pressure cylinder, a piston within said cylinder, a hollow piston rod for said piston, inlet and exhaust valves in said piston rod for controlling admission of fluid pressure to and exhaust from one side of said piston, and an electromotive device mounted upon said piston within said cylinder connected for controlling said inlet and exhaust valves.

3. In a train control block system, a brake applying control means comprising a fluid pressure cylinder, a piston within said cylinder, a fluid pressure connection to said cylinder upon one side of said piston, a valve in said piston admitting pressure to the other side thereof and an exhaust valve for the same side of said piston, and an electromotive device mounted upon said piston within said cylinder for opening said exhaust valve and closing said admission valve, and vice versa, to operate said piston.

4. In a train control block system, a brake applying control means comprising a fluid pressure cylinder, a piston within said cylinder, a fluid pressure connection to said cylinder upon one side of said piston, a hollow piston rod for said piston, a pressure equalizing valve in said piston, an exhaust

valve in said hollow piston rod, and an electromotive device mounted upon said piston within said cylinder and connected to simultaneously control said equalizing and exhaust valves.

5. In a train control block system, a brake applying means comprising a fluid pressure cylinder, a piston within said cylinder, a fluid pressure connection to said cylinder upon one side of said piston, a hollow piston rod for said piston, a pressure equalizing valve in said piston, an exhaust valve in said hollow piston rod, a common operating rod for said valves, an electromagnet having its coils mounted upon said piston, and an armature for said electromagnet connected to said common operating rod.

6. In a train control block system, a brake applying means comprising a fluid pressure cylinder, a piston within said cylinder, a fluid pressure connection to said cylinder upon one side of said piston, a hollow piston rod for said piston, said piston having an aperture in alignment with the bore of said hollow piston rod, said piston rod having an inlet port within said cylinder and an exhaust port outside of said cylinder, a valve for each of said ports, a common operating rod for said valves extending through said piston, and an electromagnet mounted upon said piston on the side opposite said piston rod and having its armature connected to said common operating rod.

7. In a train control block system, the combination with a valve for controlling the admission of motive fluid to the engine and a valve for controlling the application of the brakes, of an automatic control device comprising a fluid pressure cylinder, a piston within said cylinder, a fluid pressure connection to said cylinder on one side of said piston, a valve in said piston admitting pressure to the other side thereof and an exhaust valve for the same side of said piston, an electromotive device mounted upon said piston within said cylinder for opening said exhaust valve and closing said admission valve and vice versa to operate said piston, and connections from said piston to operate said motive control and brake valves.

8. In a train control block system, the combination with a valve for controlling the admission of motive fluid to the engine and a valve for controlling the application of the brakes, of an automatic control device comprising a fluid pressure cylinder, a piston within said cylinder, a fluid pressure connection to said cylinder on one side of said piston, a valve in said piston admitting pressure to the other side thereof and an exhaust valve for the same side of said piston, an electromotive device mounted upon said piston within said cylinder for opening said exhaust valve and closing said admission

valve and vice versa to operate said piston, an operating connection between said piston and said brake valve, a fluid pressure device for controlling said motive fluid valve, and means controlled by said piston for admitting fluid pressure to and exhausting it from said fluid pressure device.

9. In a train control system, the combination with an engineer's valve for controlling the application of the brakes, of an automatic control device comprising a fluid pressure cylinder, a piston within said cylinder, a fluid pressure connection on one side of said piston, a valve in said piston admitting pressure to the other side thereof and an exhaust valve for the same side of said piston, an electromotive device mounted upon said piston within said cylinder for operating said exhaust and said admission valves, and a connection from said piston to said engineer's valve to operate the same without interfering with the manual operation of said engineer's valve.

10. In a train control block system, the combination with a valve for controlling the admission of motive fluid to the engine and an engineer's valve for controlling the application of the brakes, of an automatic control device comprising a fluid pressure cylinder, a piston within said cylinder, means dependent upon the position of said piston for closing said motive fluid admission valve, and means connecting said piston with the engineer's valve handle, said last mentioned means comprising a movable member arranged to engage such handle on one side only, so that said handle is free to move independent of said member during the normal manual operation of said engineer's valve.

11. In a train control block system, a brake applying means comprising a fluid pressure cylinder, a piston within said cylinder, a fluid pressure connection to said cylinder upon one side of said piston, a valve in said piston admitting pressure to the other side thereof and an exhaust valve for the same side of said piston, an electromotive device for operating said piston and comprising two coils which when simultaneously energized produce no effect upon said valves, but when one only is energized said exhaust valve is opened and said admission valve is closed and vice versa to operate said piston.

12. In a train control block system, a train carried brake applying means comprising a fluid pressure cylinder, a piston within said cylinder, a fluid pressure connection to said cylinder upon one side of said piston, a valve in said piston admitting pressure to the other side thereof and an exhaust valve for the same side of said piston, an electromotive device for opening said exhaust valve and closing said admission valve and vice

- versa to operate said piston, said electro-motive device having two coils which when simultaneously energized produce no effect upon said valves but when one of which is energized said valves are operated, a source of current, coöperating fixed and movable contacts along the way and upon the train, a circuit for one of said coils which includes said source of current and said contacts, and 5 a circuit for the other of said coils which includes said source of current, said contacts and a circuit changer dependent upon danger or safety conditions along the way.
13. A train control block system comprising train control mechanism upon the train, a circuit changer and a set of train-operated contacts for each block, circuits along each block coöperating with said contacts and said circuit changer, and electrically balanced electro-motive devices on the train to govern said train control mechanism and comprising two magnets one of which is included in a local circuit through said train-operated contacts and the other of which is included in a circuit through said train-operated contacts and said circuit changer contacts.
14. A train control block system comprising train control mechanism upon the train, a circuit changer and set of train-operated contacts for each block, circuits along each block coöperating with said contacts and said circuit changer, a fluid pressure motor for operating said train control mechanism, and electrically balanced electro-motive devices on the train to admit fluid pressure to said motor to govern said train control mechanism and comprising two magnets one of which is included in a local circuit through said train-operated contacts and the other of which is included in the circuit through said train-operated contacts and said circuit changer contact.
15. In a train control block system, train carried electromagnetically governed train control mechanism including a source of current and terminal brushes, a set of train engaged contacts for each block and circuits coöperating therewith, an electromagnetic step-by-step circuit changer for each block operated by engagement of one of said brushes with one of said contacts to complete or disable an operating circuit for said mechanism to another of said contacts.
16. In a train control block system, a train carried brake applying means comprising a fluid pressure cylinder, a piston within said cylinder, a fluid pressure connection to said cylinder upon one side of said piston, 50 a valve in said piston admitting pressure to the other side thereof and an exhaust valve for the same side of said piston, an electro-motive device for opening said exhaust valve and closing said admission valve and vice versa to operate said piston, said elec-
- tromotive device having two coils which when simultaneously energized produce no effect upon said valves but when one of which is energized said valves are operated, a source of current, coöperating fixed and 70 movable contacts along the road and upon the train, a circuit for one of said coils which includes said source of current and said contacts, and a circuit for the other of said coils which includes said source of 75 current, said contacts and a step by step electromagnetic circuit changer dependent upon danger or safety conditions along the road.
17. In a train control block system, train 80 carried electromagnetically governed train control mechanism, a set of train engaged contacts for each block and circuits coöperating therewith, an electromagnetic step-by-step circuit changer for each block at adjacent ends thereof actuated from one of said contacts to complete or disable an operating circuit for said mechanism to another of said contacts, the circuit changer actuating circuit including one of the track rails and said 85 operating circuit including the other track rail.
18. In a train control block system, train carried train control mechanism, a set of train engaged contacts for each block and 90 circuits coöperating therewith, an electromagnetic circuit changer at the far end of each block for closing or breaking an operating circuit for said mechanism, one of said contacts connected to actuate the circuit 95 changer in the rear.
19. In a train control block system, train carried train control mechanism, a set of train engaged contacts for each block and circuits coöperating therewith including an 100 energizing circuit, an electro-magnetic circuit changer at the far end of each block for closing or breaking said energizing circuit for said mechanism, one of said contacts connected to complete said energizing circuit.
20. In a train control block system, train carried train control mechanism, a set of train engaged contacts for each block and circuits coöperating therewith, an electro- 110 magnetic circuit changer at the far end of each block for closing or breaking an operating circuit for said mechanism, one of said contacts connected to actuate the circuit 115 changer of the block in advance, and a contact connected to actuate the circuit changer in the rear.
21. In a train control block system, train carried train control mechanism, a set of train engaged contacts upon one side of the 120 track for each block and circuits coöperating therewith, a second set of train engaged contacts for each block and circuits coöperating therewith, an electromagnetic circuit 125 changer at the end of each block for closing 130

- or breaking an operating circuit for said mechanism, each of said sets of contacts co-operating with circuits and a circuit changer extending in direction opposite to that of 5 the other set.
22. In a train control block system, train carried train control mechanism, a set of train engaged contacts for each block near the entrance end thereof, an electromagnetic 10 circuit changer at the far end of each block for closing or breaking an operating circuit for said mechanism, and a second set of train engaged contacts for each block with co-operating circuits for operating each electromagnetic circuit changer in the opposite direction of train movement.
23. In a train control block system, train carried train control mechanism including a source of current and terminal brushes, a 15 set of contacts near the entrance of each block co-operating with said train carried brushes, an electromagnetic circuit changer at the far end of each block, a control circuit from one of said contacts to said circuit 20 changer, and an operating circuit from one of said block contacts for said mechanism which includes a conductor along the block, the contacts of said circuit changer, and track rail return.
24. In a train control block system, train carried train control mechanism including a source of current and terminal brushes, a set of contacts for each block co-operating with said train carried brushes, an electromagnetic 25 circuit changer at the far end of each block, a control circuit from one of said block contacts to said circuit changer with return by one track rail, and an operating circuit from one of said block contacts for 30 said mechanism which includes a conductor along the block, the contacts of said circuit changer and return by the other track rail.
25. In a train control system, train carried train control mechanism including a source 35 of current and terminal brushes, a set of brushes near the entrance of each block co- 40
- operating with said train carried contact, an operating circuit from one of said block contacts which includes a conductor along the block and track rail return, an electromagnetic 45 circuit changer at the far end of each block for opening and closing said operating circuit, and a control circuit for said circuit changer which includes another of said block contacts. 50
26. In a train control block system, train carried train control mechanism and contacts and a source of current therefor, a set of contacts near the entrance of each block co-operating with said train carried contacts, 55 a second set of contacts for each block at the entrance thereof going in the opposite direction, and an electromagnetic circuit changer at the end of each block for opening and closing an operating circuit for said mechanism, said circuit changer being controllable from each set of contacts by trains going in either direction. 60
27. In a train control block system, train carried train control mechanism and contacts and a source of current therefor, a set of contacts near the entrance of each block co-operating with said train carried contacts, an electromagnetic step-by-step circuit changer for each block for alternately closing 65 and breaking an operating circuit along the road for said mechanism, a control circuit from one of said contacts to said circuit changer, and an operating circuit from one of said block contacts for said mechanism 70 which includes a conductor along the block, contacts of said circuit changer, and track rail return. 75
- In testimony whereof we have hereunto set our hands in presence of two subscribing 75 witnesses.

FELIX MARY MUSY.
MELVILLE E. SULLIVAN.

Witnesses:

O. M. HEFLER,
W. E. KELLEY.

It is hereby certified that in Letters Patent No. 1,324,205, granted December 9, 1919, upon the application of Felix Mary Musy and Melville E. Sullivan, of Richmond, Virginia, for an improvement in "Railway-Train Automatic-Control Apparatus and Systems," errors appear in the printed specification requiring correction as follows: Page 2, line 96, strike out the word "rod"; page 4, line 92, strike out the word "of"; and that the said Letters Patent should be read with these corrections therein that the same may conform to the record of the case in the Patent Office.

Signed and sealed this 3d day of February, A. D., 1920.

[SEAL.]

M. H. COULSTON,
Acting Commissioner of Patents.

Cl. 246—71.
